UNITED STATES PATENT OFFICE

2,350,645

RETARDING MEANS FOR RAILWAY CAR DOORS

Arthur E. Small, Porter, Ind., assignor, by mesne assignments, to Standard Railway Equipment Manufacturing Company, a corporation of Delaware

Application September 2, 1941, Serial No. 409,206

5 Claims. (Cl. 292—68)

The invention relates to doors for railway cars and more particularly to means for preventing violent and unrestricted movement of a sliding door during service movements of the car. The usual type of sliding side door is well known in the railway car art wherein a door is movable in a horizontal direction on a track substantially parallel with the wall of the car and moves into and out of alignment with the doorway in the side wall.

Various means for supporting and moving such a sliding door are used. One of the best known is that disclosed in Gilpin Patent No. 1,902,772 of March 21, 1933, wherein rollers are rotatably mounted upon the door and a track engaged by such rollers is rigidly carried by the car. The track is provided with depressions located at the proper places so that when the door is in the full open or full closed position, the rollers are above the depressions. The rollers are thus relieved of the weight of the door and, in their places, the door is supported by engagement of rigid parts carried respectively by the door and car. The friction between such rigid parts tends to prevent movement of the door.

In recent years a combination of circumstances, such as increased train and switching speeds and heavier loading of cars, has tended to impart more violent impacts to cars during service with the result that the above mentioned frictional resistance as well as other retarding means sometimes used have become inadequate to prevent accidental door movement. Such movements are liable to cause damage to the car and to the door, as well as injury to an operator who happens to get in the way of such a moving door.

An object of my invention is to provide a retarding means for a railway car door which is operative in the full open and full closed position and in any intermediate position for preventing unrestricted and violent accidental door movements during the operation of the railway car.

Another object is to design such retarding means so that it may be easily operated by a simple operation.

A further object is to provide a simple, rugged and inexpensive retarding means which may be easily adapted to any of the conventional designs of railway car side doors now in service.

Another object is to associate a handle with the above mentioned retarding means so that when a force sufficient for moving the door is exerted upon the handle, the retarding means is automatically adjusted so as to release the door for easy movement.

Another object is to associate a handle with the retarding means in such a way that when the handle is moved to a position in which an operator can utilize it for moving the door, the retarding means is automatically released and the door may then be easily moved.

Other objects and advantages of my invention will be apparent from the following detailed description by referring to the accompanying drawings.

In the drawings:

Fig. 1 is a partial side elevation of a railway car showing the side door and one modification of the retarding means applied thereto, the retarding means being in normal position.

Fig. 2 is an enlarged view of the retarding means in the position shown in Fig. 1.

Fig. 3 is a section on line 3—3 of Fig. 2.

Fig. 4 is a view of the retarding means with the door in the position shown in Fig. 1 and with the retarding means released so that the door may be moved.

Fig. 5 is a view of the retarding means with the door in the full closed position shown in Fig. 1 and with the retarding means shown in the position in which it prevents movement of the door.

Fig. 6 is a view of the retarding means in normal position when the door is in a position intermediate the full open or full closed position.

Fig. 7 is a view of the retarding means when the door is in the intermediate position shown in Fig. 6 and when the retarding means is released to permit movement of the door.

Figs. 8 and 9 are views showing the positions taken by the retarding means for locking the door when the door is moved from the position of Fig. 6 a limited amount to the left and right, respectively.

Fig. 10 is a view similar to Fig. 2 showing a modified form of retarding means.

Fig. 11 is an elevational view of a modified form of my invention showing the retarding means at rest so that a limited movement of the door in either direction from the position shown causes the door to be locked against further movement.

Fig. 12 is a section on line 12—12 of Fig. 11.

Fig. 13 is a view similar to Fig. 12 showing the retarding means in position to permit free movement of the door in either direction.

Fig. 14 is a view similar to Fig. 11 showing another modification of my invention.

Fig. 15 is a section on line 15—15 of Fig. 14.

Fig. 16 is a view similar to Fig. 14 showing the

retarding means moved to a position wherein the door may be freely moved in either direction.

In Fig. 1, the side wall 2 has a door opening and a side door 3 is shown in a position wherein it completely or fully closes the doorway. The track 5 for supporting the door 3 is a longitudinally extending, inwardly facing channel member preferably secured to the side sill 6 of the car. A roller housing 8 is rigidly mounted upon each of the lower corners of the door 3 and rollers 9 are rotatably mounted within the housings 8 and arranged to roll upon the upper laterally extending flange 11 of the channel track 5. The track 5 is preferably provided with spaced apart depressions 12 arranged so that when the door is in the full closed position or full open position, the rollers 9 are above the depressions 12. The rollers 9 are thus relieved of the weight of the door, which weight is transferred to parts of the roller housings 8 or other rigid parts of the door which engage the track 5. The friction between such parts and the track retards movement of the door. The starting lever 14 is pivoted (15) to the door 3 and has its lower end 17 arranged to engage a starting bracket 18 secured to the track 5 for the purpose of utilizing the leverage to move the rollers 9 out of the depressions 12. Such a starting lever is more fully disclosed in Schlesinger Patent No. 1,963,152, June 19, 1934.

The retarding means is comprised, in part, by a base member 25 rigidly secured to the door 3 and provided with a rigid, outwardly extending pintle 26. A dog 28 is provided with a slot 29 which engages the pintle 26 so that such dog 28 is free to both slide and rotate upon the pintle 26. A retaining washer 31 is provided and the end of the pintle 26 is formed with a head 32 over the washer 31 for the purpose of confining the dog 28. The dog 28 includes spaced apart lugs 34, 35, the upper lug 34 being disposed above and the lower lug 35 below the upper laterally extending flange 11 of the channel track 5. A handle 37 is provided on the upper end of the dog 28 to provide a means for the lifting thereof.

When the door 3 is in the full closed or full open position and the dog 28 is resting freely, such dog takes the position shown in detail in Figs. 2 and 3. When it is desired to move the door 3 along the track, the dog 28 is moved upwardly, preferably by lifting on the handle 37, and assumes the position shown in Fig. 4. In this position, both the upper (34) and lower (35) lugs are entirely free of the track 5 and the door 3 may then be freely moved horizontally any desired distance provided the dog is held at all times substantially in the position shown in Fig. 4.

If an attempt is made to move the door toward the right from the position shown in Fig. 2 without lifting the dog 28, the upper lug 34 drags on the upper flange 11 of the track 5 and causes the dog 28 to rotate to the position shown in Fig. 5. In such position, the left hand edge 40 of the lower lug 35 engages the underside of the flange 11 and the right hand edge 41 of the upper lug 34 engages the upper side of the laterally extending flange 11 of the track 5. The dog 28 thus firmly grips the track 5 and further movement of the door toward the right is not possible. The lower side 43 of the upper lug 34 is preferably convex so that the dog 28 rotates more easily as the lug 34 is dragged over the track 5. The edges 40, 41 of the lower (35) and upper (34) lugs which engage the track 5 upon rotation of the dog are preferably relatively keen

in order to bite into the track and provide a more positive locking effect.

Figure 6 shows the dog 28 at rest when the door 3 is in some intermediate position between full open and full closed. Figure 6 differs from Figure 2 only in that the bottom edge 46 of the door 3 is spaced a greater distance above the track 5 due to the fact that the rollers 9 have been moved out of the depressions 12 and now support the door upon the undepressed part of the track 5.

Figure 7 is a view also when the door is in the above mentioned intermediate position but wherein the dog 28 has been lifted so that both the upper (34) and lower (35) lugs are free of the laterally extending flange 11 of the track 5; the door 3 may then be freely moved in either direction. When the dog 28 is resting, as shown in Figure 6, and the door 3 is moved to the left, the dragging of the upper lug 34 upon the track 5 rotates the dog 28 to the position shown in Figure 8 and the gripping thereof upon the track 5 prevents further movement of the door as hereinabove described. Similarly, if the door is moved from the position shown in Figure 6 toward the right, the dog 28, after a limited movement of the door 3, assumes the position shown in Figure 9 and further movement of the door is not possible.

In the modification shown in Fig. 10, the operation of the retarding means is similar to that heretofore described, with the exception that the downwardly facing side 50 of the pintle 51 is V-shape and the slot 53 in the dog 54 is similarly V-shape at the bottom so that when the dog 54 is lifted by hand for the purpose of freeing the lugs 34, 35 from the track 5, such movement will be in a substantially vertical direction, thereby preventing unintentional rotation of the dog with consequent accidental gripping of the track.

In the modification shown in Figures 11 to 13, the dog 57 is similar to that heretofore described and is provided with a downwardly facing hook 58 at the upper end thereof. The handle 60 is formed of preferably round rod and is made substantially in the shape of a rectangle journaled by its top side 61 in bearings formed by straps 64 secured to the door 3. A part 66 of the top side 61 of the rectangle is offset to form a hook engaging part. As shown in Figures 11 and 12, the handle 60 is hanging freely and the dog 57 is also resting freely upon the track in such a position that if an attempt is made to move the door either to the right or to the left, the dog 57 will be rotated about the pintle 59 and will grip the track 5 in the manner hereinbefore described.

In order to obtain hand clearance to get a grip on the handle 60 for the purpose of moving the door, the operator must raise the handle 60 to the position shown in Fig. 13. When the handle 60 is thus moved, the hook engaging part 66 engages the hook 58 of the dog 57 and raises the dog to the position shown in Figure 13 wherein both the upper (68) and lower (69) lugs thereof are free of the laterally extending flange 11 of the channel track member 5 and the door may then be moved freely in either direction.

In the modification shown in Figures 14 to 16, a reinforcing plate 72 is rigidly secured to the door 3 preferably by such means as the double countersunk rivets 73 through the lower frame strip 75 of the door 3. A pintle 76 is rigidly secured to and extends outwardly from the re-

inforcing plate 72. The movable member 78 of the retarding means consists of a substantially triangular plate 79 having depending therefrom a dog 81 similar to that heretofore described. The triangular plate 79 is provided with a flat inverted V slot 82 which engages the pintle 76 and the plate 79 is retained on the pintle by means of the integral head 84 thereof. In the position shown in Figure 14, the dog 81 is resting with the upper lug 85 thereof supported by the laterally extending flange 11 of the channel track 5. When the dog 81 is in this position, a limited movement of the door 3 in either direction causes the dog 81 to rotate and grip the track 5 in the manner hereinbefore described. When it is desired to move the door, a horizontal force may be exerted upon the movable member 78 by means of the rigidly attached handle 87 and the plate 79 is moved relative to the door 3 until one end of the inverted V slot 82 engages the pintle 76, as shown in Figure 16. The retarding means is moved to the position shown in Figure 16 by a force on the handle 87 which tends to move the door 3 toward the right. As the end of the inverted V slot 82 engages the pintle 76, the dog 81 is lifted to the position shown in Figure 16 wherein both the upper (85) and lower (88) lugs are clear of the laterally extending flange 11 of the track 5 and the door may then be freely moved. Force on the handle 87 toward the left would cause the right hand end of the inverted V slot 82 to engage the pintle 76 and the dog 81 would again be clear of the track flange 11. A ledge 90 on the rear side of the dog engages the lower side 91 of the reinforcing plate 72 when the dog 81 is moved upwardly for the purpose of preventing accidental rotation of the dog 81 and consequent gripping thereof on the track.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. Retarding means for a sliding door wherein said door is arranged to move longitudinally of a member having a laterally extending part, a dog, and means to rotatably mount said dog upon said door, said dog including a pair of lugs, one disposed above and the other below said laterally extending part and being spaced apart the proper distance to grip said part upon limited rotation of said dog, and a handle pivotally mounted upon said door and having an offset portion eccentrically engaging said dog, whereby when said handle is swung on its pivot said offset portion raises said dog to a position in which said lugs are clear of said part.

2. Retarding means for a sliding door wherein

said door is arranged to move longitudinally of a member having a laterally extending part, a dog, and means to rotatably mount said dog upon said door, said dog including a pair of lugs, one of said lugs having a convex portion disposed above said laterally extending part, and the other of said lugs having a portion disposed below said laterally extending part said portions being spaced apart the proper distance to grip said part upon limited rotation of said dog, a handle pivotally mounted upon said door and having an offset portion eccentrically engaging said dog, whereby when said handle is swung on its pivot said offset portion raises said dog to a position in which said lugs are clear of said part.

3. Retarding means for a sliding door wherein said door is arranged to move longitudinally of a horizontal member having a laterally extending part, a dog rotatably mounted upon said door and having a convex portion normally engaging said part, said dog also having a portion normally spaced below said part, said portions being spaced apart and disposed on opposite sides of and so as to grip said part upon limited rotation of said dog, and a handle pivotally mounted upon said door and having a protrusion engageable with said dog eccentrically, whereby when said handle is moved on its pivot said protrusion moves said dog to a position in which said portions are clear of said part.

4. Retarding means for a sliding door wherein said door is arranged to move longitudinally of a horizontal member having a laterally extending part, a dog, means to rotatably support said dog upon said door, said dog formed with a notch providing opposed spaced surfaces extending on opposite sides of said member, said surfaces being adapted to grip said member upon limited rotation of said dog, and a handle pivotally mounted upon said door and having a protrusion engageable with said dog eccentrically, whereby when said handle is moved on its pivot said protrusion moves said dog to a position in which said surfaces are clear of said part.

5. Retarding means for a sliding door wherein said door is arranged to move longitudinally of a member having a laterally extending part, a dog, means to rotatably mount said dog upon said door, said dog including a pair of lugs, one disposed above and the other below said laterally extending part and being spaced apart the proper distance to grip said part upon limited rotation of said dog, and a pivotally mounted handle usable to move the door longitudinally of said member, said handle having a part engageable with said dog eccentrically, to raise said dog upon pivotal movement of said handle to a position in which said lugs are clear of said part and to retain said lugs in said position while the door is being moved by said handle.

ARTHUR E. SMALL.
